UNITED STATES PATENT OFFICE

155,043

DESIGN FOR A BOTTLE

Javier Serra, New York, N. Y., assignor to Les Parfums De Dana, Inc., New York, N. Y., a corporation of New York

Application July 8, 1948, Serial No. 147,439

Term of patent 14 years

(Cl. D58—8)

To all whom it may concern:

Be it known that I, Javier Serra, a citizen of Spain, residing in New York city, in the county of New York and State of New York, have invented a new, original, and ornamental Design for a Bottle, of which the following is a specification, reference being had to the accompanying drawing, forming a part thereof.

In the drawing:

I claim:

The ornamental design for a bottle, as shown.

JAVIER SERRA.
